UNITED STATES PATENT OFFICE.

BERNARD J. RILEY, OF EAST NEWARK, NEW JERSEY.

TRAVELING-BAG.

SPECIFICATION forming part of Letters Patent No. 336,529, dated February 16, 1886.

Application filed November 9, 1885. Serial No. 182,192. (No model.)

To all whom it may concern:

Be it known that I, BERNARD J. RILEY, a citizen of the United States, residing at East Newark, in the county of Hudson and State 5 of New Jersey, have invented certain new and useful Improvements in Bag or Satchel Hinges and Braces; and I do hereby declare the following to be a full, clear, and exact description of the invention, such as will enable others 10 skilled in the art to which it appertains to make and use the same.

This invention has relation to hinges for bags and satchels, and has for its object to provide a combined hinge and stay which shall 15 be simple and inexpensive in its construction, and which can be readily applied to the frames of bags and satchels as ordinarily constructed.

This invention consists in the provision, as 20 a new article of manufacture, of a combined bag hinge and stay or brace, so constructed as to be applicable to the bag-frames by simply riveting the hinge thereto.

Referring to the accompanying drawing, A 25 represent the hinge-plates, connected together by a pintle, B. Each of these plates is formed with ears *a*, and to these ears are pivoted the terminals of the L-shaped metallic pieces C C, which are hinged together at D, so as to form an adjustable brace, as shown.

30 When this brace is turned down so as to lie in the plane with the leaves A A, they operate in the same way as the bag-hinge, and allow the latter to freely open and close, the pintles B and *b'* being on a line with or parallel with each other. When, however, the brace is turned up to a position at right angles with the plane of the hinge-leaves, the relation of the pintles to each other is such that the sections of the brace cannot be brought together 35 or toward each other; hence the hinge is firmly locked and cannot be closed. These

stays or braces may be applied to both the 45 hinges on a bag or satchel, or they may be applied to only one of the hinges on each bag or satchel.

Among the many advantages of this form of a hinge and brace, it may be noted that the brace is very short, and therefore does not occupy any appreciable amount of room in the bag or satchel, while at the same time it is less 50 liable to be broken than if it were of a greater length.

Another advantage possessed by this form of a brace is that, as it is a part of the hinges, it is attached to the bag or satchel without 55 defacing any part of the frame.

What I claim as new is—

1. The combination, with the bag or satchel frame, of the hinge B and the adjustable brace or stay consisting of the L-shaped pieces C C, 60 pivotally connected at their inner ends and hinged to the plates A A, substantially as described.

2. A combined hinge and hinge-stay for bags or satchels, consisting of the plates A A, pivotally connected and forming the hinge, and the L-shaped pieces C C, jointed together and hinged to the plates A A, substantially as described, so that the brace may be raised or lowered to lock or unlock the hinge. 7c

3. The combination, with the frame of a satchel or bag, of the hinge having the ears *a* *a*, and L-shaped pieces C C, pivoted to said ears and hinged together at D, substantially as shown and described. 75

In testimony whereof I affix my signature in presence of two witnesses.

BERNARD J. RILEY.
